UNITED STATES PATENT OFFICE.

FRANK D. LENNEN, OF EASTON, PENNSYLVANIA.

ROTARY EXPLOSION-ENGINE.

1,201,836.

Specification of Letters Patent. Patented Oct. 17, 1916.

Application filed July 2, 1915. Serial No. 37,733.

To all whom it may concern:

Be it known that I, FRANK D. LENNEN, a citizen of the United States, residing at Easton, in the county of Northampton and 5 State of Pennsylvania, have invented new and useful Improvements in Rotary Explosion-Engines, of which the following is a specification.

This invention relates to rotary explosion engines or internal combustion engines of 10 the turbine type wherein is employed a stationary rotor casing, a rotor mounted therein, and means for introducing exploded gas into the rotor chamber to act 15 successively on the blades of the rotor.

The chief object of the present invention is to provide in connection with such an engine, means operating automatically to compress air, force the fuel under pressure to a 20 combined mixing and combustion chamber, also forcing air under pressure to said chamber, igniting said mixture and directing the same against the rotor and finally through an exhaust port to the atmosphere.

25 With the above and other objects in view, the invention consists in the novel construction, combination and arrangement of parts, as herein described, illustrated and claimed.

In the accompanying drawings: Figure 30 1 is a vertical longitudinal section through an engine embodying the present invention. Fig. 2 is a diametrical section through the same showing the shaft and certain parts in elevation. Fig. 3 is a side elevation of the 35 rotor and its blades, showing the packing rings and strips therefor. Fig. 4 is a cross section through one of the rotor blades showing the packing means. Fig. 5 is a fragmentary plan view showing the pump 40 plunger operating mechanism.

The rotor casing as illustrated in Figs. 1 and 2 comprises an outer annular main body or peripheral section 1 formed with a water space or jacket 2 and having secured to opposite sides thereof the casing heads 3 and 4 both of which are preferably formed separately from the section 1 of the casing and secured fixedly thereto by screws or bolts 5. The casing thus formed provides a rotor 45 chamber 6 in which is mounted a rotor comprising a main body or hub 7 having extending outwardly therefrom a circular series of blades or wings 8 shown as curvilinear in cross section in order to obtain the 50 best effect of the expanding gas which impinges against the concaved faces of the

blades as indicated in Fig. 1. The rotor is mounted fast on a rotary shaft 9 which passes through the heads 3 and 4 of the casing and is journaled in one or more bearings 10 60 at opposite sides thereof and supported in any suitable manner.

11 designates a key by means of which the rotor is fastened to the shaft 9.

A portion of the rotor casing is offset 65 preferably at the top as shown at 12 and a combined mixing and combustion chamber 13 shown as cylindrical in cross section is mounted upon the rotor casing, the chamber 13 being provided with a base flange 14 for 70 that purpose. The chamber 13 is closed at both ends but one end portion of the cylinder which forms the combustion chamber is provided with a pump chamber 15 separated from the combustion chamber 13 by means 75 of a ported wall or partition 16 the port 17 of which is opened and closed by means of a check valve 18 which is held normally seated by means of a spring 19 encircling the stem 20 of said check valve, the end of 80 the stem 20 being slidable in an opening 21 in one of the heads of the cylindrical casing of the pump chamber and combustion chamber.

Operating in the pump chamber 15 is a 85 plunger 22 which extends outwardly through the adjacent head of the chamber where it is provided with a head 23 behind which is arranged a coiled expansion spring 24 for moving the plunger 22 to the initial 90 end of its stroke. Coöoperating with the plunger 22 is a rock shaft 25 having at one end an arm which operates the plunger 22 and at the other end an arm which is operated upon by a cam 26 fast on the engine 95 shaft 9, said cam 26 serving to periodically operate the plunger 22 on its working stroke, the plunger being retracted by means of the spring 24 referred to.

27 represents a fuel tank in which hydrocarbon oil may be placed and forced under pressure to a feed pipe 28 into the pump chamber 15, back flow of the fuel being prevented by means of a check valve 29.

30 designates an air compressor the air 100 from which is forced through a pipe 31 into the fuel tank 27. Air is also forced through the air pipe 32 containing a back pressure check valve 33 into the combined mixing and combustion chamber 13.

24 represents an igniter shown in the 105 form of an ordinary spark plug for ignit-

ing the compressed mixture in the combustion chamber.

In order to prevent leakage of the expanding mixture around the sides of the 5 rotor, the rotor is provided in each side thereof with a groove containing an annular split packing ring 35 formed with notches 36 to receive the inner ends of packing strips 37 set into grooves in the opposite sides of 10 each blade 8. The packing ring and strips referred to are pressed outwardly in opposite directions and against the inner surfaces of the casing heads 3 and 4 by means of expansion springs 38 extending through openings 39 in the hub and wings of the rotor as 15 shown in Fig. 4.

The operation of the engine is as follows: To primarily start the engine, it is necessary 20 to pump a certain amount of air under pressure into the fuel tank 27, the pressure there- in being afterward maintained by the air compressor 30 which is driven by any suitable means from the engine shaft. The fuel passes through the feed pipe 28 into the 25 pump chamber and is intermittently injected into the combined mixing and combustion chamber 13 and simultaneously therewith air under pressure is forced through the pipe 32 into said chamber. The compressed mix- 30 ture of air and oil is then ignited at the proper intervals and quickly exhausts by expanding through the passage leading from the combustion chamber into the rotor chamber. In the last named chamber it acts 35 against the concaved sides of the wings 8 and finally passes out through the exhaust port 40 to the atmosphere. The outer edges of the wings 8 are arranged at such a distance from the inside periphery of the rotor 40 casing that the gas may escape between said edges and the casing and reach the exhaust port.

The engine hereinabove described is simple in construction, efficient in operation, 45 embodies a minimum number of parts and is self-starting after a certain amount of pressure is obtained in the fuel tank. This initial pressure may be produced by means of a hand pump or any other suitable device. 50 After the mixing chamber reaches a certain temperature, the engine will operate under kerosene as well as gasolene. The engine is smooth in its running qualities and is prac-

tically noiseless there being no valves or valve rods.

While I have only shown a single mixing and combustion chamber, it will of course be understood that two or more of such chambers may be used, arranged at intervals around the rotor casing and furthermore, 60 one or more rotors and casings may be provided in connection with the same engine shaft 9 thereby multiplying the power of the engine as a whole. Where the engine is used on an automobile and subjected to vibration and jolting, instead of pumping the air directly from the compressor to the fuel tank, an air storage tank may be used in conjunction with and located between the air compressor and the fuel tank 27 or the 65 tank 27 may be made of sufficient size to admit of a partition dividing the tank into an air storage chamber and a fuel chamber. 70

What I claim is:—

In a rotary explosion engine, the combination 75 of a rotor, a shaft on which said rotor is fast, a substantially cylindrical rotor casing through which said shaft passes, a combined mixing and combustion chamber located exteriorly of the rotor casing and provided with a passage leading therefrom into the rotor casing and disposed at an angle to the radius of the rotor, wings on said rotor which successively pass by said passage, a pump chamber at one end 80 of the combustion chamber, a partition between said combustion chamber and pump chamber, a spring seated back pressure check valve in said partition, a plunger operating in said pump chamber, a fuel supply tank, an air compressor communicating with said tank, a fuel feed pipe leading from said tank to the pump chamber and containing a check valve, a compressed air pipe communicating with said combustion chamber, means for igniting the charge in the combustion chamber, a cam on the rotor shaft, and means operated thereby for effecting a working stroke of said plunger for each blade of the rotor. 85

In testimony whereof I affix my signature in presence of two witnesses.

FRANK D. LENNEN.
